UNITED STATES PATENT OFFICE

133,457

DESIGN FOR AN APPLIQUÉ EMBLEM OR SIMILAR ARTICLE FOR WEARING AP- PAREL

Eugenia R. Staber, Wichita Falls, Tex.

Application March 26, 1942, Serial No. 106,331

Term of patent 7 years

To all whom it may concern:

Be it known that I, Eugenia R. Staber, a citizen of the United States, residing at Wichita Falls, State of Texas, have invented a new, original, and ornamental Design for an Appliquéd Emblem or Similar Article for Wearing Apparel, of which the following is a specification, reference being had to the accompanying drawing, forming part thereof.

Fig. 1 is a front elevational view of an appliquéd emblem showing my design.

Fig. 2 is an edge view thereof.

I claim:

The ornamental design for an appliquéd emblem or similar article for wearing apparel, as shown.

EUGENIA R. STABER.
